ABSTRACT

A pitter for removing whole or half pits from clingstone drupe halves in which relative movement between a drupe half and a member on the pitter toward each other, from a spaced position, is effected, until said member engages the planar surface of the drupe half around the exposed pit, and thereafter, continued movement in the same direction automatically actuates a mechanism that causes pit engaging elements on said member to engage the side of the pit adhered to the pit cavity, and to apply yieldable outward pressure on the pit to tension the fibers holding the pit in said pit cavity. At the same time such pressure is applied said elements are revolved relative to the pit to break the tensioned fibers and to rotate the pit relative to the peach half when adhesion is weakened, and said member and elements are thereafter automatically actuated to withdraw and to release the detached pit from the half, and to restore the member to its spaced position preparatory to another pitting operation.

The invention also includes the provision of a plurality of pitters operatively connected with a single source of power for simultaneously pitting a row of drupe halves employing the above structure and for simultaneously positioning and removing successive rows of drupe halves to and from said pitting position.

DRUPE PITTER

This is a division of copending application Ser. No. 814,118, filed Apr. 7, 1969, now U.S. Pat. No. 3,583,456.

SUMMARY

The present apparatus is adapted to be employed as an auxiliary to torque type pitters to pit the drupe halves that may not be pitted by the torque type pitters due to split pits, in which case it may be called a repitter, or all of the drupes including their pits may be bisected and then pitted by the apparatus, and in a single pitting machine there may be any number of simultaneously actuated pitting units, each adapted to separate a whole or half pit from the pit cavity without loss of flesh irrespective of differences in the sizes of the pits so that the pitted products are substantially indistinguishable from those pitted by the true torque method.

As drupes including their pits may be bisected at a much higher rate than they can be pitted, it is seen that where a pitting machine is adapted to simultaneously pit a plurality of drupe halves, such as eight or more, and which halves are automatically oriented and fed to the pitting unit at approximately the same rate as they are singly fed to conventional pitters for pitting single peaches, the volume of drupes pitted is materially increased over the ordinary systems heretofore used, and the drupe halves have all the desirable characteristics of halves pitted by the strictly torque type pitter.

One object of the invention is the provision of a clingstone drupe pitter that includes one or more pitting heads each including a member supported for reciprocation into and out of engagement with a stationarily held drupe half which head includes pit engaging elements movable into engagement with the side of the pit adherently held in the pit cavity of the stationary drupe half and which elements are automatically actuated by movement of said member after its engagement with the drupe half to revolve relative to the pit to free the pit from the drupe half, which reciprocable movement of said member and pit engaging members including revolving of the latter is automatic and actuated from a single source of power.

Another object of the invention is the provision of a pitter that is an improvement over the drupe pitter disclosed in U.S. Pat. No. 3,540,507 of Nov. 17, 1970.

Other objects and advantages will appear in the detailed description and drawings.

DESCRIPTION OF DRAWINGS

FIG. 1 is a part elevational, part cross sectional view taken through a housing enclosing part of the driving means for the pitting heads.

FIG. 2 is a top plan view of the housing of FIG. 1 partly broken away to show the driving elements inside the housing, with part of such elements in cross section.

FIG. 3 is an enlarged side elevational view of one of the pitting heads, the upper end portions of several of which are shown in FIG. 1.

FIG. 4 is a side elevational view of the pitting head of FIG. 3 as seen at a right angle to the latter.

FIG. 5 is a bottom plan view of the pitting head of FIG. 4.

FIG. 6 is a fragmentary enlarged elevational view of the lower end of the pitting head of FIG. 3 showing in dot-dash lines, the action of the pit engaging tines in a pitting operation and the forces applied to the pit being shown by arrows.

FIG. 7 is an enlarged fragmentary, part sectional, part elevational view of a part of the cup-type conveyor showing several drupe supporting cups in a row in positions below several of the pitting heads of FIGS. 3, 4.

FIG. 8 is a top plan view of one of several of the conveyor cups as seen from line 8-8 of FIG. 7.

FIG. 9 is an enlarged cross sectional view of one of the conveyor cups of the transverse rows thereof taken along line 9-9 of FIG. 7.

DETAILED DESCRIPTION

SUPPORT AND VERTICAL RECIPROCACTION OF PITTING HEADS

5 Secured on rocker shaft 26 (FIG. 2) is one end of each of a plurality of corresponding arms 70. The opposite outer end of each arm is formed with a yoke to provide horizontally spaced arms 71 (FIGS. 1-3), each having a roller 72 thereon disposed on the oppositely facing sides thereof, which rollers are positioned in an annular outwardly opening recess 73 formed in collar 74 (FIGS. 1, 3, 4) of one of the pitting heads 75 of a pitting mechanism. A horizontally-elongated metal strip 76 (FIG. 2) extends the length of the row of pitting heads, and longitudinally of the rocker shaft 26, and is clamped between the respective arms 70 and said shaft, which strip automatically aligns the arms 70 longitudinally of the row thereof.

The rocking of rocker shaft 26 is under the influence of a cam, on a continuously rotating shaft shown and described in copending application Ser. No. 814,118, which cam controls the oscillatory movement of the arms 70 and consequently the lowering and elevating of pitter heads 75, as will later be explained more in detail.

A detailed description of one pitting head and its support and actuating means will suffice for the others except that a single gear will actuate each separate pair of pitting heads.

The pitting heads 75 depend from a horizontally-elongated housing 77 (FIGS. 1, 2) which housing includes an end compartment 78 at one end thereof (FIG. 9).

30 Said housing 77 has an upper wall 79 and a lower wall 80 (FIG. 2) and end walls 81, 82. Bearings 83, 84 respectively in end walls 81, 82 support the ends of a horizontally-extending shaft 86. One end portion 87 of said shaft 86 extends into compartment 78.

35 The pitting heads 75 each have upward extensions generally designated 90 connected therewith, (FIG. 1) that extend upwardly through the lower and upper walls 80, 79 of housing 77, and the collars 74 of the pitting heads are adjacent to and below said lower wall 80.

40 Each collar 74 is coaxial with, and reciprocably supported, on a central vertical rod 92 (FIGS. 3, 4). A spline 93 connects the collar 74 with rod 92 for rotation of the rod and the collar together, while permitting reciprocable movement of the collar on the rod.

45 A split coupling 94 connects the upper end of rod 92 with the lower end of a hollow shaft 95 that is integral with and in upward extension of the half 96 of said coupling (FIG. 4), the other half 97 being generally semi-cylindrical, and connected to the upper end of rod 92 by screws 98. Halves 96, 97 and the portion of rod 92 between them are formed with a coaxial bore for a screw 99 that extends therethrough, one end of said screw being in threaded engagement with the portion of the bore that is in the half 96.

50 The structure of coupling 90 enables quick removal and replacement of a pitting head 75 outside the housing 77, if necessary.

55 Hollow shaft 95 (FIG. 1) extends into the lower end portion of an outer rotary shaft 100 and is connected with shaft 100 by a spline 101 with said outer shaft for rotation together with the latter while permitting axial reciprocatory movement of shaft 95 relative to shaft 100.

60 The outer shaft 100 is supported at its lower and upper ends in bearings 104, 105 (FIG. 1) that are respectively carried by the lower wall 80 and upper wall 79 of housing 77.

65 Outer shaft 100 terminates approximately at the upper side of an upper bearing 105.

70 Threadedly extending into and connected with the upper end of shaft 95 is the lower end of a spindle shaft 106 that is spaced within the outer shaft 100. The upper end portion of spindle shaft 106 is slidably and rotatably supported in a vertical bearing 107, which bearing, in turn, is threadedly connected with an annular nut 108 through which the bearing 107 extends, which nut is adapted to be tightened against the upper edges of the outer shaft 100 for rotation with the latter.

The upper side of nut 108 is formed with an annular upwardly opening recess in which a shock absorbent ring 109 of rubber or similar material is secured, and an inverted cup-like hood 110 is releasably secured on the upper end of the spindle shaft 106, within which the upper end of the upper bearing 107 is adapted to be received upon downward movement of the spindle shaft. The lower annular edge of the hood 110 may engage the shock absorbent ring 109 upon lowering of the spindle shaft 106 to the lower end of its movement. In any event the ring 109 will limit downward movement of the hood and said spindle shaft.

A pinion 111 is formed on the outer tubular shaft 100 at a point spaced between the upper and lower walls of housing 77.

A helical spring 112, coaxial with spindle shaft 106 is around the latter in the space between said shaft 106 and outer shaft 100. This spring reacts between the upper end of the hollow shaft 95 and the lower end of the upper bearing 107 to yieldably resist upward movement of the hollow shaft 95 or to yieldably urge it downwardly. Upward movement of the collar 74 through rocking of rock shaft 26 moves the spindle upwardly to its elevated position.

The spindle shaft assemblies, each of which include the lower hollow shaft 95 and the connector for connecting the latter with a pitting head 75, are arranged in pairs in a row that is alongside the horizontal shaft 86 that, in turn, extends through housing 77 longitudinally of the latter.

ROTATION OF PITTING HEADS

Directly below shaft 86 and equally spaced from the spindle shafts of each pair of the latter, the lower wall 80 is formed with upwardly projecting bosses 115 (FIG. 1), each of which supports a vertical, stationary stub shaft 116. Each stub shaft 116 carries bearings 117 on their upper ends that rotatably support a set of gears comprising spur gear 118 and a bevel gear 119 coaxial therewith and secured thereto. The teeth of the spur gears are in mesh with the teeth of pinions 111 on the outer shaft 100 of the spindle shaft assembly of each pair, while the teeth of the bevel gear 119 are each in mesh with the teeth of a bevel gear 120 secured on shaft 86. Upon rotation of the shaft 86 in one direction the spindle shafts 100 and pitting heads 74 will be simultaneously rotated in one direction, and upon reverse rotation of shaft 86 the spindle shafts and pitting heads will be rotated simultaneously in the opposite direction.

A spur gear 123 is keyed on the end of shaft 86 that projects into the end compartment 78 of housing 77, (FIG. 1), the teeth of which gear 123 are in mesh with the teeth of a segment gear, the back of which is seen in FIG. 1 on arm 125, which arm 125 is supported by a bearing 126 (FIG. 1) on a pivot 127, the latter, in turn, being supported at its ends in two opposite walls of compartment 78 (FIG. 1). Arm 125 has a portion offset to one side, which portion carries a cam follower 129. A face cam 130 (FIG. 1) on the main camshaft continuously rotating that controls reciprocation of the pitting heads and oscillation of arm 125, extends into the compartment 78 and follower 129 is in the cam track 131 of said cam (FIG. 1). Upon oscillation of arm 125 and of the segment gear thereon, under the influence of cam 130, the shaft 86 will be oscillated to cause the pitting heads 74 to be rotated 180° in one direction and then immediately 180° in a reverse direction at equally spaced intervals of time provided for by the contour of cam track 131.

Each spindle shaft assembly hereinbefore described and each pitting head, may be generally described as a pitting head assembly, and the shaft 86 in housing 77 and the various pieces therein and in compartment 78, including the actuating means therefor, may be generally called the pitting head drive assembly.

THE PITTING HEADS

Specifically referring to FIGS. 3, 4, each pitter head 75 includes a central, vertically elongated shaft 92, the upper end of which is connected by the coupling 94 with lower end of the hollow shaft 95 that extends into the housing 77 (FIG. 1). The

collar 74 is below said coupling and the shaft 92 reciprocally extends through said collar, but the shaft 92 is connected with said collar by the spline 93 on shaft 92 for holding said collar and shaft against rotation relative to each other.

Said collar 74 is the one having the radially outwardly opening recess 73 in which rollers 72 are positioned, said rollers being carried on arm 70 that is secured to the rocker shaft 26 (FIG. 2).

Integral with the collar 74 is a base block 136 through which shaft 92 also slidably extends, and said base block has parallel opposite flat sides against each of which the upper end of a stationary cam plate 137 is secured, and from which each plate depends. Plates 137 are planar and are in spaced opposed relation at opposite sides of and spaced from the shaft 92, and their opposed faces are formed with vertically-extending cam tracks 138 (FIG. 3) each having oppositely outwardly extending lower end portions 139. These cam tracks are positioned at opposite sides of a vertical plane that is coincidental with the axis of shaft 92 and perpendicular to the planes of plates 137, and are identical except for being offset at opposite sides of said vertical plane and that their lower end portions 139 extend outwardly relative to said plane in opposite directions.

10 15 20 25 30 35 40 45 50 55 60 65 70

Integral with the collar 74 is a base block 136 through which shaft 92 also slidably extends, and said base block has parallel opposite flat sides against each of which the upper end of a stationary cam plate 137 is secured, and from which each plate depends. Plates 137 are planar and are in spaced opposed relation at opposite sides of and spaced from the shaft 92, and their opposed faces are formed with vertically-extending cam tracks 138 (FIG. 3) each having oppositely outwardly extending lower end portions 139. These cam tracks are positioned at opposite sides of a vertical plane that is coincidental with the axis of shaft 92 and perpendicular to the planes of plates 137, and are identical except for being offset at opposite sides of said vertical plane and that their lower end portions 139 extend outwardly relative to said plane in opposite directions.

10 15 20 25 30 35 40 45 50 55 60 65 70

A pair of cranks, generally designated 140, are positioned at opposite sides of the shaft 92, each crank having a relatively short vertically-extending arm 141 and a longer horizontally-extending arm 142 (FIG. 3). The shorter arms 141 extend upwardly from their juncture with the longer arms, and horizontal pivots 143 at said junctures pivotally connect the cranks with members 144 that are rigidly secured to the shaft 92 at opposite sides of the latter, said shaft being flattened at said opposite sides (FIG. 4) from the upper edges of said members, downwardly, for securement of said members against said flat sides by coaxial screws 145 (FIG. 3) extending into the shaft. The shaft 92 may be rabbeted longitudinally thereof along opposite side edges of the flattened opposite sides to receive flanges 146 along the side edges of the members 144 (FIG. 5) to secure said members rigid with the shaft against rotation about the axis of said screws 145.

Collar 74 is in its uppermost position on shaft 92 when it is against the coupling 94, and when in said uppermost position, the upper end of the shorter crank arm 141 of each crank is

45 adjacent to and in opposed relation to the open side of the lower portion 139 of a cam track 138 (FIG. 3). A cam follower 147, rotatably carried on said upper end of each shorter crank arm 141, extends into said lower portion 139 of the cam track adjacent thereto. The pivots 143 are spaced below the lower ends of cam plates 137 and the longer crank arms 142 extend from said pivots 143 horizontally across opposite sides of shaft 92. Cranks 140 are of the same structure and arms 142 extend horizontally across opposite sides of shaft 92 from pivots 143 to points spaced equal distances outwardly of shaft 134.

55 60 65 70

The outer ends of the longer crank arms 142 are formed with through bores for pivots 150 that are respectively integral with cross elements 151 (FIGS. 11, 12). One element is at each of the opposite sides of shaft 92, and the upper end of a rod 152 reciprocably extends through each element 151. Rods 152 extend convergently downwardly to points at opposite sides of the lower end portion of shaft 92 and a flat-sided enlargement or head 153, rigid with the lower end portion of each rod, extends between an opposed pair of ears 154 that are integral with and project from one side of a clevis generally designated 156, having an opposed pair of arms 157, 158 projecting from its opposite side. A pivot 159 extends through ears 154 pivotally connecting the lower end of each rod 152 to one of the clevises (FIGS. 3, 4, 6).

Coaxial horizontal pivots 160 (FIGS. 4, 6) threadedly extending into the lower end of shaft 92 and projecting oppositely outwardly therefrom, extend through the arms 157, 158 of the arms of clevises 156 pivotally connecting said arms with said lower end of shaft 92.

A helical or coil spring 161 (FIG. 4) around each rod 152 reacts between a flange on a collar 162 that is slidable on each rod adjacent to and below each element 151 and a flange on a similar collar 163 adjacent enlargement or head 153. The end of each rod adjacent to each enlargement 153 is threaded, and the flange on each collar 163 is against a nut 164 threaded out the lower end of each rod. The upper end of each rod 152 is also threaded, and a nut 165 is on the threaded portion projecting from the upper side of each element 151. Thus the tension of springs 161 can be adjusted and said tension is such that the nuts 165 are yieldably held against the upper sides of elements 151 and the clevises 156 will simultaneously pivot clockwise about one of the pivots 160 for the right-hand clevis in FIG. 6, and counterclockwise for the left-hand clevis upon downward movement of the outer ends of the longer arms 142, but may yield if unexpected predetermined resistance to said pivotal movement of one of the clevises is encountered.

Each clevis 156 includes a head or cross piece 168 (FIG. 4) from which said ears 154 and arms 157, 158 project. The latter project convergently downwardly from each cross piece 168 to opposite sides of the lower portions of shaft 92 (FIG. 3).

The aforesaid cross pieces 168 have flat sides that face outwardly of the lower end of shaft 92, and the upper enlarged end portion 169 of a downwardly projecting tine 170 (FIG. 4) is secured against each said flat sides by a screw 171. The flat side against which said portion 169 is held is actually the bottom of a recess formed in each cross piece having straight parallel sides, and the enlarged portion 169 (FIG. 4) of the tine is rectangular with straight side edges against said sides of the recess, so the tine is rigid on said cross piece insofar as rotation about screw 171 is concerned.

Secured on the lower end portion of shaft 92 at the sides that are at right angles to the sides against which members 144 are secured are the upper end portions 172 of a pair of downwardly-extending supports 173 (FIG. 4) against the lower ends of which is secured a flat horizontally-disposed annular member 174 (FIG. 5) by screws 175. The lower end portions of supports 173 are offset to one side of each of the coaxial pivots 160 (FIG. 6) in the same direction circumferentially of the member 174 to avoid the latter and the ends of arms 157, 158.

When the collar 74 on shaft 92 at the upper end of the pitting head is in its uppermost position, the terminal lower ends of the tines 170 are approximately even with the lower surface of the annular member 174 and are within opposingly opening recesses 176 formed in the opposed radially inner sides of said member.

Tines 170 preferably are slightly curved toward each other in a downward direction and come to a point at their lower terminal ends. From said lower ends they become progressively wider (FIG. 4) in an upward direction to the enlarged upper portion 169. The pitting head rotates in one direction about the axis of shaft 92 during the effective pitting operation, thus each tine has a leading edge 177 and a trailing edge 178. Said trailing edge of both tines may be substantially straight, axially of shaft 92 and substantially in a vertical plane bisecting the shaft longitudinally thereof, while the leading edge is slightly slanted outwardly of said plane from its pointed end to the upper portion 169 (FIG. 4) and the sides of each is slightly bevelled from edge 177 at 179 so that said leading edge will not engage the pit of a drupe that is between the pair of teeth, as will be explained more in detail later on.

Shaft 92 is formed with a central downwardly opening bore 180 in which a rod 181 (FIG. 6) is vertically reciprocable. The upper end 182 of said rod 181 (FIG. 3) is enlarged, as is the upper portion of bore 180, and said enlargement is adapted to abut an axially upwardly facing shoulder at the juncture between the enlarged upper end of bore 180 and the lesser diameter lower end to restrict downward movement of said rod. An expansion coil spring 183 reacts between head 182 and rod 181 and a closure in the upper end of said bore 180 to yieldably urge rod 181 downwardly. A transversely elongated

pit-engaging element 184 (FIGS. 5, 6) rotatably secured by a screw 185 on the lower end of rod 181 is positioned with its lower surface slightly below the plane of lower surface of the annular member 174.

- 5 Each intermittent rotation of shaft 36 of conveyor 6 by rotation of the index plate 37, as hereinbefore described, moves the drupe supporting cups 5 of each transverse row thereof (FIG. 7) into alignment with, and below, the row of pitting heads 75 with the lower ends of the pitting heads spaced above 10 the cups and above the drupe halves that are in said cups.

DRUPE CONVEYOR AND SUPPORT FOR DRUPE HALVES DURING PITTING

- 15 An endless conveyor 6 (FIG. 7) extends at one end over a pair of sprocket wheels 186 adjacent opposite ends of a shaft 40 on one end of which shaft is secured an intermittently rotated index plate 37, and the other end of the conveyor extends over a similar pair of sprocket wheels on another shaft. 20 A pair of endless sprocket chains 187 extend over said pairs of sprocket wheels and metal strips 188 (FIG. 8) extend between the chains and are secured to links of the latter, thus providing an endless row of said strips in parallel side-by-side relation. Each strip is formed with a row of openings 189 (FIG. 9) in 25 each of which an annular casting 190 for each cup 5 extends. Each strip 188 has flanges on sides 191 along its longitudinally-extending edges that are directed inwardly relative to the endless chains whereby each strip is of channel shape in cross-sectional contour, the flanges or sides 191 providing rigidity for the strips. Radially outwardly projecting ears 192 (FIG. 8) on each casting 190 is adapted to overlie the outer surface of each strip around each opening and screws 193 (FIG. 9) threaded into openings in said ears extend through 30 openings in said ears and secure the castings to each strip. 35 Each cup 5 is of rubber or rubber-like plastic material and is of conical shape with the larger diameter end open and facing outwardly of the conveyor, and the smaller diameter end of each cup is closed by an imperforate bottom wall 195 of said material (FIG. 9). The side walls 196 of each cup are formed with straight ribs 197 of uniform width extending divergently relative to each other from said bottom wall outwardly to the outer side of said cup. Said ribs are rounded on their outer sides to prevent injury to the convex outer surfaces of drupe 40 halves seated thereagainst, and to hold such halves against rotation relative to the cups when said convex surfaces are forced thereagainst.

- The radially outermost portion or rim 198 of each cup is relatively thick, and spaced inwardly from said rim is a depending cylindrical portion 199 that is adapted to seat in an annular outwardly opening recess 200 in the casting 190. The radial inner side of said portion 199 is formed with radially inwardly projecting segments 201 adapted to snap into complementarily formed recesses in the inner side wall of each recess 200 for releasably holding the cups in the castings 190.

- Lugs 204 (FIG. 7), secured to the ends of the strip 188 project from the same sides of said strips as flanges 191, and the outer ends of said lugs are connected to links of chains 187, and said chains are slidably supported on tracks 205 (FIG. 7) 60 that are, in turn, secured on angle strips 206 of the frame 10. The strips that are below the pitting heads are supported on members 207, which members are stationary on a cross frame member 208 that is secured at its ends to said angle strips 206 centrally between its ends, strips 188 are each provided with a bearing element 209 slidable on a piece 210 secured to said cross frame member 208.

- By this structure the cups of the rows of cups are adequately supported from below at the pitting station for resisting downward movement when the pitting heads descend into contact with the drupe halves 1 (FIG. 9) in the cups 5.

PITTING OPERATION

- The collar 74 on each pitting head and all of the elements 75 connected with or mounted on the vertical shaft 92 including

the annular drupe engaging member 174 on the lower end of said head, are adapted to move downwardly, as a unit, with the tines 170 retracted in the position shown in FIGS. 11-14.

Immediately upon the lower surface of the annular member 174 engaging the flat or planar upper surface of a drupe half supported in a cup 5, the collar 74 of each pitting head and cam plates 137 thereon, will continue downward movement under the influence of rollers 72 on arm 70 (FIG. 8). The shaft 92 that carries the cam followers 147 will be stopped by the engagement of annular member 174 with the planar upper face of the drupe half, but continued downward movement of the cam plates 137 will actuate followers 146 so that cranks 140 will cause the outer pointed ends of the tines 170 to start to move along paths 213 (FIG. 6) until the tines are in pit-engaging positions 214. The tines are moved to said positions 214 under the influence of movement of cam followers 147 in the lower portions 139 of cam tracks 138, and springs 161 (FIG. 3) reacting against the lower ends of rods 152 (FIG. 5) will result in applying an upward yieldable pressure of tines 170, as indicated by arrows 216 (FIG. 6), against the convex underside of pit 217, thus tending to draw the pit out of the pit cavity in the drupe half while the body of the drupe half is held against the annular member 174. The fibers connecting the pit with the pit cavity are placed under tension, and at the same time the element 184, which may be called a "foot," extends across the pit approximately from edge-to-edge, and spring 183 yieldably maintains the foot against the pit, although the spring 183 that provides such tension, is light relative to the tension of springs 161.

The limit of downward movement of the collar 74 on each pitting head is determined by the limit of downward movement of the hood 110 on the upper end of spindle shaft 106 (FIG. 1). The lower surface of the hood sides are adapted to engage the bumper rings when the downward limit of the movement of the pitting is reached, although normally the pitting head would not reach the downward limit of its movement, even when the peach half was relatively small.

When the cam followers 147 are in the vertical upper portions of cam tracks 138 the tines will remain in the final position to which they have been moved, which may vary somewhat, according to the size of the pit. The smaller the diameter of the drupe, the farther the head 75 will move downwardly before the tines are actuated, and the tines are actuated during the one-inch downward movement of the collar following the engagement between the annular member 174 and the planar upper surface of the peach.

After such final downward movement of the collar and the drupe half is firmly seated in a cup, the cam 130 on camshaft 19 will actuate the cam follower 129 and segmental gear 124 to rotate the pitting heads 180° in each of two opposite directions to break the fibers connecting the pits in the pit cavities, and to remove the pits by a torque action resulting from weakening the attachment of the pits to the sides of the pit cavities and the frictional engagement between the pit and the tines. The double bevelled leading edges of the tines provides a wedge-effect as the tines move around the pit and this effect, together with the tension of springs 161 tending to draw the pit out of the pit cavity and the torque force applied to the pit, combine to break the tensioned fibers connecting the pit to the body of the drupe forming the pit cavity and to rotate the pit relative to the body of the drupe half. The tines are in frictional engagement with the pit during rotation of the head to free the pit. This method of engaging the pits and breaking them loose is similar to that shown and described in U.S. Pat. No. 3,540,507, of Nov. 17, 1970.

The timing effected by the cams hereinbefore described is such that, after an advance of the conveyor to position a row of cups having drupe halves therein below the pitting heads, the conveyor is stationary, and at the same time the heads 75 are moved down to effect gripping of the bodies of the drupe halves between the conveyor cups 5 and the annular members 174. While the conveyor is still stationary the heads 75 are rotated to remove the pits, after which the heads 75 are moved

upwardly and the conveyor is moved for positioning another row of drupe-filled cups to a position below the row of pitting heads.

We claim:

1. Apparatus for removing a pit from a drupe half, which half has a planar surface on one side and a pit cavity therein with the pit adhered in said cavity, and a generally hemispherical convex surface on the other side extending to said planar surface, comprising:
  - a. a pitting head comprising an elongated member supported for reciprocable movement longitudinally thereof between an initial position in which one end is spaced from a drupe half, and a drupe engaging position, in which said one end is in engagement with said planar surface around a pit in said pit cavity and in which drupe engaging position further movement of said member toward said half is stopped by said half when such half is held stationary on said axis relative to said reciprocable movement in a pit-removing position with said planar surface facing said member, and means for holding such drupe half stationary in said pit-removing position,
  - b. pit-engaging means adjacent to said one end supported for movement from a retracted position out of said drupe half into said half through said planar surface thereon to pit-engaging position in engagement with the side of said pit within said pit cavity at points spaced from the edges of said cavity, said movement of said pit-engaging means being in a direction for applying pressure against said pit outwardly of said pit cavity during said further movement and after said engagement at said points,
  - c. actuating means for said pit-engaging means operatively connected with said member for movement therewith from said initial position of said member to a second position in a direction toward a drupe half held in said pit-removing position until further movement is stopped by engagement of said end of said member with said planar surface of such drupe, said actuating means being supported for further movement from said second position in said direction after said member is so stopped and means operatively connected with said member for reciprocating the latter including moving said actuating means during said further movement thereof,
  - d. means connecting said pit-engaging means with said actuating means for moving said pit-engaging means from said retracted position to said pit-engaging position and in said direction for applying said pressure against said pit during said further movement of said actuating means, and
  - e. said member, actuating means, and said pit-engaging member being connected for rotation as a unit about longitudinal axis of said member when said pit-engaging means is in engagement with a pit at the end of said further movement of said actuating means, and said member is rotated, and means connected with said member for so rotating the latter.
2. In apparatus as defined in claim 1;
- f. said means connecting said pit-engaging means with said actuating means comprises cam means respectively on said actuating means and on said member movable relative to each other upon moving of said actuating means during said further movement thereof.
3. In apparatus as defined in claim 1;
- g. separate spring means respectively connected with said pit-engaging means and with said actuating means during said further movement of said actuating means for yieldably returning said pit-engaging means to said retracted position, and for yieldably holding said member against a drupe half during said further movement of said actuating means and during return of said actuating means to said second position.
4. In apparatus as defined in claim 2;
- h. said member comprising an inner shaft, and said actuating means comprising an outer body supported thereon for reciprocable movement longitudinally thereof,

- i. said pit-engaging means comprising a pair of opposingly positioned tines at opposite sides of said one end of said shaft pivotally supported on said one end for arcuate movement about a common axis through said planar surface and into said pit-engaging relation when said member is in pit removing position. 5
- j. said cam means comprising cam tracks rigid on said outer body, and cam followers on said cam tracks operatively connected with said tines, said tracks being contoured to move said tines to and from said pit-engaging relation upon reciprocable movement of said body on said shaft. 10
- 5. In apparatus as defined in claim 1;
- f. a stationary frame supporting said member for said vertical reciprocable movement, 15
- g. said means operatively connected with said member for reciprocating it comprising a rocker arm pivotally supported on said frame for oscillatory movement of one end thereof, and means at said one end connected with said member, and rotatable power-driven cam means 20
- rotatably supported on said frame and operatively connected with said rocker arm for rocking said arm upon rotation of said power-driven cam means.
- 6. Apparatus for removing pits from drupe halves, each of which has a planar surface on one side and a generally hemispherical convex surface on the other side extending to said planar surface with a pit cavity in said planar surface having a pit held therein exposed for removal from said cavity; 25
- a. a stationary frame,
- b. a straight row of elongated, corresponding vertically disposed pitting heads each including a member supported thereon for vertically reciprocable movement in the same direction in the plane of said row on vertically disposed axes, 30
- c. a row of supports for supporting drupe halves with their planar surfaces directed upwardly, said row being parallel with said pitting heads providing one support below each head with each support being on one of said axes, and means for supporting said supports in positions equally 35

40

- spaced below said heads for simultaneous engagement of the lower ends of each head with the planar surface of each drupe half on each support at the end of downward movement of said heads,
  - d. pit-engaging and removing elements on each of said heads supported thereon for simultaneous movement into engagement with the side of the pit in each half that is within the pit cavity in each drupe and for upward movement relative to said lower end of said head and outwardly of said half, during said engagement of said lower end of each head with a drupe half for forcing said pit in a direction outwardly of each half,
  - e. element-actuating means on each head supported thereon actuatable for movement relative thereto connected with said pit-engaging and removing elements for so moving said pit engaging and removing elements upon said engagement between the lower end of each head and said planar surface on the drupe half therebelow,
  - f. means connected with said heads and with said pit actuating means for moving said respective heads simultaneously and for simultaneously actuating said pit actuating means.
  - 7. In an apparatus as defined in claim 6;
  - g. said means for moving said respective heads simultaneously and for simultaneously actuating said actuating means including a single power driven shaft and a cam on said shaft operatively connected with said member and with said actuating means.
  - 8. In apparatus as defined in claim 7;
  - h. head and element rotating means operatively connecting said power-driven shaft with said head and elements for simultaneously rotating said head and revolving said elements about the axes of said respective heads relative to said supports and the drupe halves supported therein during engagement of the lower ends of said heads with the drupe halves in said support and during said engagement of said elements with the pits in said drupe halves.
